UNITED STATES PATENT OFFICE.

RICHARD C. KREBS, OF CHICAGO, ILLINOIS.

LATCH FOR DRILL-HEADS OF HANDPIECES OF DENTAL ENGINES.

1,142,443.

Specification of Letters Patent.

Patented June 8, 1915.

Application filed October 23, 1914. Serial No. 868,178.

To all whom it may concern:

Be it known that I, RICHARD C. KREBS, a citizen of the United States, and a resident of Chicago, Cook county, State of Illinois, have invented certain new and useful Improvements in Latches for Drill-Heads of Handpieces of Dental Engines, of which the following is declared to be a full, clear, and exact description.

10 This invention relates to hand pieces of dental engines, and more particularly, to the latch thereof which is used for holding the tool in place in the chuck of the head.

15 The present forms of latches are difficult to manipulate and do not effectively hold the tool in place after they are worn slightly.

20 The object of this invention is to overcome such difficulties, and to provide a latch of improved construction, which shall be cheap, simple and effective in operation.

To such ends, this invention consists in the several novel features of construction, arrangement and combination of parts hereinafter fully set forth and claimed.

25 The invention is clearly illustrated in the drawing furnished herewith, of which:—

Figure 1 is a side elevation of the hand piece of a dental engine, showing a simple embodiment of the present invention applied thereto; Fig. 2 is an enlarged side view of the head thereof, partly broken away to show certain parts of the interior construction; Fig. 3 is an end view, looking in the direction of the arrow, 3, in Fig. 2; 35 Fig. 4 is a plan of the part seen in Fig. 2, and Fig. 5 is a perspective view of the latch.

Referring to said drawings, 10 designates the handle of a hand piece of a dental engine, which may be of the usual and well known form of construction, having a head, 11, at one end, in which is a chuck, 12, arranged to be rotated by suitable, flexible shafting, in accordance with the usual, well

45 known practice in hand pieces of dental engines. The tool, 13, used in connection with devices of this kind, has a shank, 14, which is inserted into the chuck, 12, and has a flattened portion, 15, for engagement with a flattened portion, 16, of the chuck, to insure its rotation therewith, and at the said upper portion of said shank, is a reduced neck, 17, above which is a head, 18, thus leaving a groove between the head, 18, and shank, 14, 50 as shown in Fig. 2. The head, 11, of the hand piece is formed with a slot, 19, near its

upper edge, as seen in Fig. 3, said slot extending inward from one side of the head, for the reception of one part of the latch. The parts thus far described constitute a 60 hand piece of ordinary and well known construction and require no further description, so far as this specification is concerned.

The latch, 20, which constitutes the subject matter of the present invention, has a 65 flat portion, 21, slidably seated in the groove, 19, of the head, 11, and a portion, 22, forming a thumb piece, lying above the part, 23, of the head, 12, which overlies the slot, 19. The flat, lower portion of the latch, 21, has 70 a lengthwise extending slot, 24, at its rear end, through which extends a screw, 25, for limiting the lengthwise movement of the latch, said screw passing through the overhanging part, 23, and into the head, 11. The 75 forward end of the latch, 20, is also provided with a slot, 26, for receiving the neck, 17, of the tool shank, 14, the head, 18, of the shank, being arranged to rest upon the forks of the flat portion, 20, adjacent said slot, 26. 80

The latch is preferably made of sheet metal stamped up into the form shown, and the upper thumb piece part, 22, is connected to the bottom part, 20, by a curved, connecting portion, 27, while its other end is formed 85 with a bent down part, as at 28, said parts 27, 28, engaging with the side of the head, 11, and preventing transverse movement of the latch. Preferably, the upper thumb piece portion is formed with a downwardly 90 extending, dented portion, 29, which enters a hole, 30, in the overlying part, 23, of the head, and registering with the chuck, and said dented portion bears upon the head, 18, of the tool shank, when inserted in the 95 chuck. This downwardly dented portion serves the purpose of preventing accidental lengthwise movement of the latch after it has been moved into engagement with the tool, and also steadies the tool, because of its 100 pressure upon its end.

In use, a suitable tool is forced into the chuck from the lower end, until it engages with the square portion, 16, thereof, the neck at this time being co-incident with the slot, 19, of the head, 11. Prior to this time, the latch is withdrawn to the position shown in dotted lines in Fig. 4, and after the tool has been inserted in the chuck, the user places his thumb upon the overhanging portion, 22, of the latch, and moves it forward until the depressed portion, 29, enters the 105 110

hole, 30, the forked ends of the latch at this time straddling the neck, 17, of the tool shank and underlying the head, 18, thereof, thus preventing the withdrawal of the tool.

5 More or less variation of the exact details of construction is possible without departing from the spirit of this invention, and I desire, therefore, not to limit myself to the exact form of construction shown and described, but intend in the following claims to point out all of the invention disclosed herein.

I claim as new and desire to secure by Letters Patent:

- 15 1. In combination with the hand piece of a dental engine and having a transversely extending slot in its head which is covered by the top of the head, and a chuck therebelow for the reception of a tool shank 20 having a reduced neck at its upper end, arranged to register with said slot, of a latch member for said tool shank, having a main member slidably secured in said slot, and being slotted for the reception of the neck of 25 the shank, and a thumb piece lying outside of the head and connected to said main member, said latch member being held on said head against lateral movement with respect thereto.
- 30 2. In combination with the hand piece of a dental engine and having a transversely extending slot in its head which is covered by the top of the head, and a chuck therebelow for the reception of a tool shank 35 having a reduced neck at its upper end, arranged to register with said slot, of a latch member for said tool shank, having a main member slidably secured in said slot, and being slotted for the reception of the neck of 40 the shank, and a thumb piece lying outside of the head and connected to said main member, said latch member being held on said head against lateral movement with respect thereto, said thumb piece having a

downwardly depressed portion engaging the 45 end of said shank.

3. In combination with the hand piece of a dental engine and having a transversely extending slot in its head, and a chuck therebelow for the reception of a tool shank having a reduced neck at its upper end, arranged to register with said slot, of a latch member for said tool shank, having a flat member slidably mounted in said slot, said flat member having a slotted end arranged 55 to receive the reduced neck of the tool shank, and also a slot at its other end, a screw secured in said head and extending through said second named slot, said flat portion having also a thumb piece portion 60 bent up from one edge thereof, and overlying said head, the free edge of said thumb piece portion having a downwardly bent tongue for engaging the side of the head.

4. A latch for hand pieces of dental engines, comprising a flat portion, formed with two lengthwise extending openings, one edge of said portion having a narrow part bent up and terminating in a thumb piece lying approximately parallel with said 70 flat portion, said thumb piece having a downwardly bent tongue opposite said narrow edge portion.

5. A latch for hand pieces of dental engines, comprising a flat portion, formed with two lengthwise extending openings, one edge of said portion having a narrow part bent up and terminating in a thumb piece lying approximately parallel with said flat portion, said thumb piece having a downwardly 80 bent tongue opposite said narrow edge portion, and having also a central, downwardly extending dented portion.

RICHARD C. KREBS.
